United States Patent Office

Des. 188,645
Patented Aug. 16, 1960

188,645

SHOWER HEAD OR SIMILAR ARTICLE

Herbert V. Kohler, Kohler, Wis., assignor to Kohler Co.,
Kohler, Wis., a corporation of Wisconsin

Filed Oct. 13, 1958, Ser. No. 52,961

Term of patent 14 years

(Cl. D91—3)

Fig. 1

Fig. 2

Fig. 3

Fig. 1 is a perspective view of a shower head or similar article, showing my new design;

Fig. 2 is an elevational view of the same; and

Fig. 3 is a bottom plan view of the shower head.

The dominant features of the design reside in the portions shown in full lines.

I claim:

The ornamental design for a shower head or similar article, as shown and described.
